ELLICOTT D. AVERELL, OF NEW YORK, N. Y.

Letters Patent No. 65,153, dated May 28, 1867.

IMPROVED LATH FOR PLASTERING.

The Schedule referred to in these Letters Patent and making part of the same.

TO ALL WHOM IT MAY CONCERN:

Be it known that I, ELLICOTT D. AVERELL, of the city, county, and State of New York, have invented a new and useful Improvement in Lath for Plastering; and I do hereby declare that the following is a full, clear, and exact description of the same, reference being had to the accompanying drawings, making a portion of this specification, in which—

Figure 1 is a side view of a piece of lath constructed according to my invention.

Figure 2 is a longitudinal transverse section of the same.

Figure 3 is a transverse section taken at right angles to fig. 2.

Similar letters of reference indicate corresponding parts in all the figures.

This invention consists in the construction of a lath for plaster ceilings or walls, with countersunk holes or apertures, formed by punching or other suitable means, in such manner as to secure the permanent retention of the plaster upon the lath in a much more effectual manner than has been the case with the lath ordinarily in use.

To enable others to understand the nature and construction of my invention, I will proceed to describe it with reference to the drawings.

The lath is made in strips, A, of any suitable wood, and of any desired or proper length, breadth, and thickness. These strips or laths are perforated with a number of holes or apertures, A, which are situated at any required distance from each other throughout the entire length and breadth of the strip of lath, and which extend entirely through the same from one of the flat sides thereof to the other; the ends of these holes or apertures A' at one side of the lath being considerably larger than the ends at the other side of the said lath, so that the apertures are made of countersunk form, or, in other words, are formed with bevelled sides D, as shown more fully in fig. 1, which represents that side of the lath which is placed innermost when used. The apertures A are made preferably of an oblong form, as shown in the aforesaid fig. 1, but may be of square, circular, or any other suitable shape, as may be desired. It is designed that these holes or apertures A shall be formed by means of a punch corresponding in size and shape with the outer or small ends of the apertures to be formed in the lath, and operated by any suitable mechanism, the said punch being used in connection with a suitable table for supporting the lath, furnished with a slot or recess of a larger size than the punch, and arranged below the same and in such manner that the punch being forced through the lath, forces out a portion thereof, and thus forms one of the apertures A' therein, the part punched out being forced through the slot or recess in the supporting table aforesaid, the said recess, by its increased size as compared with the punch, enabling the latter to punch out a greater area from the inner side of the lath than from the outer side thereof, thus giving to the aperture thus formed the countersunk form hereinbefore described, at the same time that the portion of wood removed from the lath, being torn out from the inner side of the lath in irregular lines, the bevelled sides of the aperture A are made of rough and irregular contour, which increases the efficiency of the countersunk apertures A in holding the plaster upon the lath; this method of perforating the lath also enabling it to be manufactured at a very moderate cost. The aperture A may, however, be formed in the lath by any other suitable means, if desired.

The lath as thus constructed is secured upon the wall or ceiling in any ordinary or suitable manner, with that side outward at which the small or narrow ends of the apertures A are situated. The plaster is then spread upon such outer surface of the lath, a portion thereof passing into and through the aforesaid countersunk apertures, and, hardening therein, is thus dove-tailed into the said apertures, the plaster being by these means much more securely and permanently secured upon the lath than would be the case if the sides of the aperture A were not made of bevelled form as hereinbefore fully described, or, in other words, if the aperture A were not countersunk in substantially the manner herein set forth.

What I claim as new, and desire to secure by Letters Patent, is—

A lath constructed with countersunk apertures A', substantially as herein set forth for the purpose specified.

ELLICOTT D. AVERELL.
